LOUDSPEAKER ENCLOSURE

Gordon L. Duern, Elmira, Ontario, and Michael N. Baldwin, Kitchener, Ontario, Canada, assignors to Electrohome Limited, Kitchener, Ontario, Canada

Filed May 27, 1968, Ser. No. 12,092

Term of patent 14 years

Int. Cl. D14—01

U.S. Cl. D26—14

FIG. 1

FIG. 2

FIG. 3

FIGURE 1 is a front perspective view of a loudspeaker enclosure showing our new design;

FIGURE 2 is a bottom plan view thereof; and

FIGURE 3 is an enlarged fragmentary detail view in dotted outline of the speaker grille, which is intended to uniformly cover the entire cylindrical area of the speaker enclosure.

The dominant features of our design resides in those portions shown in full lines in the drawing.

We claim:

The ornamental design for a loudspeaker enclosure, as shown and described.
